UNITED STATES PATENT OFFICE.

HUGO LENTZ, OF BERLIN, GERMANY.

MULTIPLE-IMPACT TURBINE.

No. 797,130.

Specification of Letters Patent.

Patented Aug. 15, 1905.

Application filed March 31, 1905. Serial No. 263,109.

To all whom it may concern:

Be it known that I, HUGO LENTZ, a subject of the German Emperor, residing at 10 and 11 Potsdamerstrasse, in the city of Berlin, German Empire, have invented a new and useful Improvement in Multiple-Impact Turbines; and I do hereby declare the following to be a full, clear, and exact description of the same.

My invention relates to multiple-impact turbines, and has for its object the increasing of the economy of the same.

The preferred form of apparatus embodying my invention, as well as certain diagrams illustrating the principle of operation thereof, are illustrated in the accompanying sheet of drawings, in which—

Figure 1 is a diagram showing the line of discharge of the steam from a turbine-wheel at varying rates of speed. Figs. 2, 3, and 4 are diagrams of the forces involved at such different rates of speed. Fig. 5 is a detail view in section of a turbine-engine to which my invention has been applied.

Throughout the drawings like reference-letters indicate like parts.

It is well known that when a jet of steam or gas is injected through a nozzle or passage-way, as b , so as to strike the blades or buckets of a rotating turbine-wheel a , the direction and velocity of the discharged steam after it leaves said buckets vary according to the relative speeds of the steam-jet and the wheel-buckets. The graphical representation of the velocity and direction of the steam will be a line which completes the triangle of forces, the other sides of which are represented by the velocity and direction of travel of the buckets and the velocity and direction of travel of the discharged steam, if said buckets were held stationary. In Fig. 3, for instance, w_{II} represents the velocity and direction of travel of the steam particles rebounding from stationary bucket a , u_{II} represents the direction of travel and velocity of the bucket a , and c_{II} the resultant velocity and direction of travel of a particle of steam which strikes said bucket when revolving at said speed u_{II} . If the bucket is stationary, the line representing the bucket travel of course reduces to zero, and the two lines w_{II} and c_{II} coincide and become w_I and c_I , as shown in Fig. 2. If the speed of the bucket is increased, the diagram takes the form shown in Fig. 4, where c_{III} is the line of travel of the steam particle. These causes produce the various series of parallel jets I,

II, and III, as shown in Fig. 1, assuming of course that all the buckets a have the same configuration and inclination. In the case of a single-impact turbine this phenomenon does not require any special attention further perhaps than to make sure that the discharge-orifice is wide enough to include the different points of discharge of the steam; but in multiple-impact turbines in which the steam is used two or more times, being led back to the turbine-wheel at another point after having been discharged from the blades at one point, it becomes necessary, if the efficiency of the apparatus is to be preserved, to make sure that the steam discharged at these various speeds of rotation shall all be properly taken care of and turned into a common direction of discharge, which is of course the medial line of the passage-way leading the steam back to the turbine-wheel, as shown at c in Fig. 5. My invention accomplishes this by the use of a series of curved vanes d_I , d_{II} , and d_{III} , (shown in Fig. 5,) which are located along the line of travel of the turbine-wheel upon the discharge side, the first one, d_I , corresponding in shape and location to the path followed by the discharged steam when the bucket a is stationary, the last one, d_{III} , corresponding in shape and location to the line of discharge of steam when the turbine is at its maximum velocity and the others, d_{II} , being located at intermediate points to correspond to intermediate speeds of rotation. As shown, these vanes are curved, so as to receive tangentially the steam delivered from the buckets of the turbine-wheel and gradually deflect the same until at the moment of leaving the other edge of the vane the steam has a direction of travel coincident with the medial line of the steam-passage c .

The mode of operation of my invention is of course clear from the foregoing description. In the case of turbines used on locomotives, ships, and other cases where varying speeds are necessary and it is often required to start up a turbine from the condition of rest my invention if employed enables the guide-vane d_I to take care of the steam discharged at the beginning of operations and the vanes d_{II} to similarly receive and control the discharged steam, as the speed of the turbine increases until at its maximum the steam is received and guided by the vane d_{III} . In every case the discharged steam is turned so as to follow the direction of the arrow in the passage-way c with the least possible loss of

velocity, and so is enabled to exert its maximum power at its second impact upon the buckets of the turbine-wheel.

It is evident, of course, that the principle of my invention can be embodied in many and various forms of construction, and I do not limit myself to the particular construction of turbine shown in the drawings.

Having therefore described my invention, what I claim as new, and desire to protect by Letters Patent, is—

1. A steam-turbine having upon the discharge side of the turbine-wheel a series of guide-vanes whose angles of inclination to the plane of rotation of the wheel vary from that of the path followed by the discharged steam when the turbine-wheel is stationary up to that followed when the turbine-wheel is rotating at its maximum speed.

2. A steam-turbine having upon the discharge side of the turbine-wheel a series of guide-vanes whose angles of inclination to the plane of rotation of the wheel vary from that of the path followed by the discharged steam when the turbine-wheel is stationary up to that followed when the turbine-wheel is rotating at its maximum speed, said vanes be-

ing located along the line of travel of turbine-wheel, the one corresponding to the path of stationary discharge being first and the one corresponding to the maximum-velocity discharge being last.

3. A steam-turbine having upon the discharge side of the turbine-wheel a series of guide-vanes each of which is inclined to correspond to the direction of steam discharged at one of a given series of speeds of turbine revolution.

4. A multiple-impact steam-turbine having upon the discharge side of the turbine-wheel and at the mouth of the steam-passage there provided a series of guide-vanes curved to receive tangentially the steam delivered from the buckets of the turbine-wheel at varying speeds of revolution and deliver the same in a common direction.

In testimony whereof I have signed my name to this specification in the presence of two subscribing witnesses.

HUGO LENTZ.
